METHOD AND APPARATUS FOR THE SIMULTANEOUS RECORDING OR REPRODUCTION OF MOTION AND SOUND

Application filed January 28, 1927, Serial No. 164,351, and in Italy April 15, 1926.

The present invention has for its object improvements relating to the simultaneous recording and reproduction of speech (or more particularly sound) and motion by means of a single film upon which are recorded in successive images:

Firstly, photographically, and in the usual manner, the motions to be reproduced;

Secondly, photographically also, but continuously, the speech (or more particularly sound), which accompanies the action.

For this purpose, the film prepared according to the present invention, comprises, in each of the pictures, a space for recording the scene,—the latter being taken and projected in the usual manner—and also a space for recording the voice.

For recording the sound, a small flame is employed, the luminous intensity of which is influenced by the amplitude and frequency of the vibrations of a membrane or diaphragm, for example, that of a telephone receiver, the variations in luminous intensity of the flame being recorded upon the film.

During the taking of the picture, the displacement of the film is effected in the ordinary manner and the usual shutter is used with a slight modification to be more particularly described hereafter.

During the projection the pictures are thrown upon the screen in the usual manner, and at the same time the strip or strips of the film which carry the record of the sound, supply, by means of a selenium or light-sensitive cell, upon which the light passing through them is thrown, the varying current which causes a telephone receiver to be operated.

In the accompanying drawings which illustrate the invention:

Fig. 1 shows the manometric casing with a small flame influenced by a telephone receiver.

Fig. 2 shows the plan of a device for amplification applicable to the telephone receiver.

Fig. 3 is a view in elevation of the shutter disc.

Fig. 4 shows, in elevation, the shutter de-

vice with eccentric controlling the reciprocatory movements of the movable diaphragm.

Fig. 5 shows the position in relation to the film of the two diaphragms, one fixed and the other movable, of the recording device, at the moment when the film is about to unroll for recording an image.

Fig. 6 shows the position of these diaphragms when this unrolling is finished and at the moment when the film is about to be exposed to the light from the condenser.

Fig. 7 shows the positions of the two diaphragms at the end of the period of exposure of the film.

Fig. 8 shows the diagrammatic arrangement of the apparatus for simultaneous recording motion and sound.

As will be seen from the drawing (Fig. 1) the manometric casing which varies the intensity of the flame for photographically recording sound is constituted by a chamber 1, in to which the gas is introduced by the pipe 2; this chamber serves as a telephone receiver and is closed by the two plates 3 and 4, separated by a very small interval.

The inner plate does not vibrate; it is provided with a small orifice 5 which allows of the passage of the gas between the two plates; it is traversed by the polar horns of an electromagnet 6, the ends of the poles coming very near to the plate 4.

The plate 4 is the vibrating membrane of the casing; it carries at its centre a tube 7 which is joined to the jet 8 by means of a tubular, flexible connection 9, made, for example, of rubber.

The jet being integral with the cover 10 of the chamber 1 is thus rendered completely independent of the vibrating plate; with this device the annoying vibrations arising from the inertia of the piece or pieces supported by the plate 4 are avoided. The latter can alter its shape freely under the combined action of the pressure of the gas contained in the casing and of the varying attraction of the electromagnet 6.

As shown in Fig. 2, the electromagnet 6, instead of being connected directly to the telephone receiver, can be energized by a device such as that which is shown diagram-

matically, comprising an amplifier 12 with two low frequency lamps, interposed in the circuit of the microphone 11. Any other suitable device for amplifying could, however, be applied.

5 The position of the poles of the electromagnet 6 in relation to the vibrating membrane 4, can be regulated (see Fig. 1) by means of a screw 13 or by any other suitable device.

10 The rays of light coming from the vibrating flame of the jet 8, suitably directed, are guided on to the diaphragms by which the projection of the light upon the parts of the 15 film reserved for recording the sound, is made.

15 This photographic record must necessarily be made upon the sensitive face of the film upon which the photographic images of the 20 successive pictures for the reproduction of motion are also recorded.

25 The film used being generally of the usual commercial width, it is indispensable that the shutter disc which allows of or intercepts the passage of the rays of light coming from without to the film, shall also allow, and this in a continuous manner, the passage of the rays of light coming from the manometric casing.

30 For this purpose, the shutter disc 14, is shaped as shown in Fig. 3, that is to say that, in addition to the cut-away portion 15 which corresponds, according to the angular speed of the disc, to the length of exposure of the 35 film for the impression of the images and the photographic recording of the sounds during the same time, it is provided with a circular slot 16, having the same centre as the axis of rotation of the disc, of a suitable 40 length of arc and the mean radius of which is of a length equal to the distance which separates the axis of the shutter from the perpendicular traced to the middle of the diaphragm which ensures the recording of the 45 sounds during the displacement of the film.

50 The diaphragms through which the rays of light coming from the vibrating flame are thrown upon the film, are two in number: The fixed one 17 (Figs. 3 and 4) serves for the projection of these rays during displacement of the film, the other, movable, 18, allows of the passage of the rays of light during the time of exposure of the film to the light from the condenser for recording views.

55 The movable diaphragm 18 is carried by a shutter 19 (Fig. 4) which can be displaced vertically under the action of a circular member 20, integral with the axis D of the shutter disc 14 and mounted eccentrically upon the 60 latter. This member 20 rotates in an aperture 21 provided in the shutter 19, the width of which aperture is equal to the diameter of the eccentric 20 which corresponds to the length of the displacement of the film in 65 order to pass from one image to another.

The shutter 19 is of such a suitable shape that it never obscures the fixed diaphragm 17 during its own movement. The shutter disc 14 is located upon the spindle D in such a position that the commencement of obscuration of the condenser O coincides with the raised position of the movable slot 18, that is to say with the raised position of the reciprocating shutter 19.

70 The shutter being in motion, it will be readily understood that, as long as the film is exposed in front of the condenser O, that is during the passage before the condenser of the cut-away arc α , the diaphragm 18, which, contrary to the diaphragm 17, receives the light of the lamp continuously, will allow the rays of light coming from the latter to pass, in such a manner that they can register impressions upon the longitudinal strip of the film, and during this time it will traverse 80 the straight path necessary to pass from the position shown in Fig. 6 to that shown in Fig. 7.

75 As soon as the shutter 14 on account of its rotary movement has cut off the rays of light coming through the condenser from outside, it will cut off at the same time the rays of the lamp emitted through the movable diaphragm, the slot 16 will unmask the fixed diaphragm and the rays of light emitted through the latter will register impressions upon a second longitudinal strip of the film during the period of unrolling of the latter, this period corresponding to the time taken up by the passage of the slot of arc β .

85 As can be seen in Figs. 5, 6 and 7, the film 22 is an ordinary film of the usual commercial width, universally employed; it comprises, in the example shown, the two ordinary lateral strips 23 provided with holes for moving the film, two continuous strips 24-24' arranged on one side for recording the sound, and the ordinary spaces 25 for receiving the successive images. Since the 90 dimensions of these spaces are diminished on one side in consequence of the presence of the strips 24-24', transverse strips 26 are left between them, which strips, in the 95 method of carrying out the invention here shown, will not receive any impression, so 100 that the image retains its usual shape.

105 The strip 24 is reserved for the impression of the rays of light passing through the movable diaphragm 18 and the strip 24' is intended to receive the rays passing through 110 the fixed diaphragm 17.

115 It will be readily understood that the strips 24-24' can be arranged respectively on both sides of the film or both placed on one side or the other, internally or externally to the device for moving the film; the longitudinal strip 24 can otherwise be replaced by a transverse strip arranged between two photographs of successive images, the shutter controlling the reciprocatory movement of the 120

diaphragm 18 moving in this case transversely and not longitudinally.

At the moment when the part A of the film (Fig. 5) has just received an impression, the period of exposure in front of the condenser being ended, the film continues to unroll in order to bring the part B in front of the condenser; at this moment the diaphragms 17 and 18 occupy the positions shown in the figure, the slot of the fixed diaphragm 17 resting horizontally at the height of the axis O of the condenser, the slot of the movable diaphragm 18 being located at the height of the transverse strip 26, which, as has already been said, will according to the method of carrying out the invention receive no impression.

Fig. 6 shows the positions of the two diaphragms, when, on account of the unrolling of the film, the part B has taken the place of the part A. At this moment, the movable diaphragm 18, controlled by the eccentric, has followed the movement of the film and has taken up the position shown in the figure.

During the exposure of the part B in front of the condenser, the diaphragm 18, actuated, as has been said, by a reciprocatory movement, is raised again to take up its initial position, the time taken by the diaphragm to traverse this path corresponding exactly to the length of the exposure of the film.

It is easily understood that under these conditions there will be no gap in the recording of the sounds, the record being effected by the movable diaphragm during the length of exposure of the film to the condenser, and by the fixed diaphragm during the displacement of the film for passing from one image to another. During projection the vibrations transmitted by the selenium or light-sensitive cell to the telephone transmitter, will have ample volume.

The device, illustrated diagrammatically in Fig. 8, shows in what manner the members serving for recording pictures and sounds simultaneously are combined. The condenser 27 for taking the pictures, having the axis O, forms the image upon the part 25 of the film 22 reserved for this purpose; the light 28 coming from the manometric casing and suitably deflected by means of a mirror or a prism 29, reaches the strips 24-24' of the film and is distributed over a length corresponding to each image by the shutter 19 actuated, as already stated, by a reciprocatory motion.

The arrangement of the apparatus for taking pictures shown in Fig. 8 serves also substantially for projection. It suffices, in fact, to imagine that instead of the condenser 27 an apparatus for projection is applied and that, within the chamber 30 enclosing the device, a lamp is arranged in the space 31, behind the film. A light-sensitive cell is then placed in the position of the jet 8 of the manometric casing.

The devices which form the object of the invention could, of course, undergo modifications both in their shape and arrangement, the members, of which the functions have just been described, and which are shown in the accompanying drawings, having been chosen merely by way of example for the application of the invention.

In particular, a single movable diaphragm could be used in certain cases, the shapes and dimensions of the slots in the fixed and movable diaphragms may be altered as desired, the method for producing reciprocatory motion of the movable diaphragm can be modified, the shape and dimensions of the shutter supporting the movable diaphragm can vary according to the apparatuses, the manometric casing may be of any suitable dimensions and the amplifying device of any kind without abandoning the characteristics of the invention.

It will be readily understood that the device for photographically recording sound can be applied, not only in combination with the recording of images, but also alone or in combination with the photographic or other recording of any phenomenon in scientific or industrial spheres.

We claim:—

1. In synchronized motion picture and sound apparatus, comprising in combination, a picture aperture, means for feeding a film in step by step progression past said picture aperture, in the usual manner for receiving a series of ocular-images, said film having a sound receiving strip adjacent the ocular-image receiving portion, a shutter obscuring said picture aperture during the moving periods of the film, between successive ocular-images, a source of light, the luminous intensity of which is varied in accordance with suitable sound responsive means, apertured diaphragms, one fixed and the other movable rectilinearly in the opposite direction to that of the progress of the film, said diaphragms and shutter being cooperably arranged as to obscure the aperture in the movable diaphragm and to uncover the aperture in the fixed diaphragm during the moving periods of the film, and to obscure the aperture in the fixed diaphragm and uncover the aperture in the movable diaphragm during the stationary periods of the film, whereby a continuous sound record is made irrespective of the intermittent character of the recording of the ocular images upon the film.

2. In synchronized motion picture and sound apparatus, comprising in combination, a picture aperture, means for feeding a film in step by step progression past said picture aperture, in the usual manner for receiving a series of ocular-images, said film having a sound receiving strip adjacent the ocular-image receiving portion, a shutter obscuring said picture aperture during the moving

periods of the film, between successive ocular-images, a source of light, the luminous intensity of which is varied in accordance with suitable sound responsive means, aper-tured diaphragms, one fixed and the other
5 movable rectilinearly in the opposite direc-tion to that of the progress of the film, a second shutter carrying said movable dia-phragm comprising a plate, an eccentric ac-tuating said plate to move the same reciprocably and operatively connected to the film feeding means said shutter overlying the fixed diaphragm but so shaped as not to ob-scure said fixed diaphragm, said diaphragms
10 and first shutter cooperating to obscure the aperture in the movable diaphragm and un-cover the aperture in the fixed diaphragm during the moving periods of the film and to obscure the aperture in the fixed dia-phragm and uncover the aperture in the mov-
15 able diaphragm during the stationary periods of the film, whereby a continuous sound rec-ord is made irrespective of the intermittent character of the recording of the ocular-
20 images upon the film.
